INVENTOR:

George B. M. Smith

BY

Robert W. Pearson

ATTORNEY.

UNITED STATES PATENT OFFICE.

GEORGE B. M. SMITH, OF TORRANCE, CALIFORNIA.

EXPANSION PISTON FOR PUMPS.

Application filed March 25, 1924. Serial No. 701,749.

To all whom it may concern:

Be it known that I, GEORGE B. M. SMITH, a citizen of the United States, residing at Torrance, in the county of Los Angeles and 5 State of California, have invented certain new and useful Improvements in Expansion Pistons for Pumps, of which the following is a specification.

This invention relates to pistons and more 10 particularly to pump pistons.

The main object of the invention is to provide an expansible pump which may be readily expanded to take up wear so as to properly fit the pump cylinder.

15 A more particular object is to provide a pump piston of the character stated which will be simple in construction, inexpensive to manufacture and efficient in operation, and which may be readily assembled and 20 adjusted.

Other objects and advantages will be made manifest in the following specification for an embodiment of the invention illustrated in the accompanying drawings, in which:

25 Figure 1 is a vertical longitudinal section of my pump piston, and a pump cylinder in which the piston is mounted to reciprocate.

Figure 2 is a cross section of my piston 30 taken on line 2—2 of Figure 1.

Referring to the drawings in which like characters of reference designate similar parts, the pump cylinder 1 has been shown, and a piston rod 2 of standard construction is being used. My piston is mounted on the end portion of said rod in said cylinder 35 1 and comprises an upper head 3, a lower head 4, an externally threaded extension 5 depending axially from said upper head, a rubber washer 6, jaws 7, a plug 8, and a nut 9 which screws on the lower end of said piston rod.

The upper head 3 and its threaded extension 5 are provided with an axial conical 45 bore 10, through which is extended the conical portion 11 of the piston rod 2, the upper face of said head engaging the annular shoulder 12 on said rod at the upper end of said conical portion. The lower head 4 50 is provided with a cylindrical axial bore 13 through which extends the lower cylindrical end 14 of the piston rod 2, the upper face of said head engaging the lower end of the extension and the annular shoulder 15 on

the piston rod 2 between the lower end of 55 the conical portion 11 and the upper end of the lower end portion 14. The jaws 7 are provided with straight cylindrical outer faces 16 and with conical inner faces 17 which converge upwardly. The plug 8 has 60 a threaded axial opening 18 in threaded engagement with the threaded extension 5, and the outer face 19 is conical to engage the inner conical surface 17 of the jaws 7, whereby the plug 8 is wedged between the 65 extension 5 and the jaws 7, which jaws surround the plug and extension. The jaws 7 are provided with annular grooves 20 in their peripheries in which are fitted split 70 spring rings 21 for holding the jaws 7 assembled on the plug 8, and the washer 6 surrounds the jaws 7. The plug 8, jaws 7 and washer 6 are placed between the heads 3 and 4 which engage the upper and lower 75 ends of said jaws and washer. The nut 9 engages the lower face of the lower head 4 and causes the upper face of the head to engage the shoulder 15, jaws 7 and washer 6, whereby the head 3 is held against the shoulder 12, and the jaws 7 and washer 6 80 are clamped between the heads 3 and 4. The plug 8 is provided with sockets 22 to receive pins 23 projecting from the upper face of the upper head 3, whereby the plug 8 may be screwed on the extension 5 or un- 85 screwed therefrom, when the lower head 4 is rotated. The head 4 is provided with sockets 24 to receive the ends of a wrench 25 whereby the head 4 upon loosing the nut 9 may be rotated to rotate the plug 8 90 as hereinbefore described.

Upon screwing the plug 8 upwardly on the extension 5 the plug 8 wedges the jaws 7 outwardly, and said jaws expand the washer 6 outwardly into contact with the 95 interior of the cylinder 1, thus taking up the wear between the cylinder and the piston and causing the said piston to fit the cylinder.

Having thus described my invention what 100 I claim is:

In combination, a piston rod formed with a shoulder, a piston comprising an upper head formed with a threaded extension, said head and extension having an axial bore to 105 receive the piston rod, a wedge shaped plug on said extension in threaded engagement therewith, jaws surrounding said plug and

having wedging inner surfaces engaging the lower head having sockets for receiving a
wedging outer surface of said plug, a wrench, and a nut screwed on the lower end
washer surrounding said jaws, said upper of said piston rod against said lower head. 10
head engaging the shoulder on said rod, said
5 plug having sockets in its lower end, a lower head on said piston rod, pins on said lower head engaging said sockets in said plug, said
In testimony whereof I affix my signature.

GEORGE B. M. SMITH.
